UNITED STATES PATENT OFFICE.

LEAH JASLOW, OF BROOKLYN, NEW YORK.

CHILD'S GARMENT.

1,395,115.

Specification of Letters Patent. Patented Oct. 25, 1921.

Application filed January 18, 1921. Serial No. 438,097.

To all whom it may concern:

Be it known that I, LEAH JASLOW, a citizen of Russia, residing at 1665 42d street, Brooklyn, New York, have invented new and 5 useful Improvements in Children's Garments, of which the following is a specification.

My invention relates to children's garments of the type usually designated combination wash suits and particularly to the 10 trousers portion of the suit and the waist or blouse to which the trousers are attached.

There has always been a demand, and 15 there now is a continually increasing demand for a child's garment which is so constructed as to enable a small child to dress itself without assistance.

It is common knowledge that a young 20 child can with facility button or otherwise fasten such portions of its clothes as are at the front of the body and in view. The difficulty arises when the child has to reach behind its back for the fastening means. An object of my invention is to provide a child's 25 garment wherein all the fastening means will be conveniently arranged at the front of the body and within view of the wearer.

A further object of my invention is to 30 provide a child's garment which is at once attractive, comfortable and inexpensive to manufacture.

In accordance with my invention I make 35 the suit in two parts so that either the waist or blouse portion or the trousers portion thereof may be worn independently of the remaining portion. This is an advantage in connection with the laundering of either portion of the suit.

With these objects in view the invention 40 consists of the novel construction and arrangements hereinafter described with reference to the accompanying drawings forming part of this specification, which drawings show a prepared embodiment of my invention.

Figure 1 is a front view of a child's garment showing the waist portion attached to the trousers portion by means of my invention.

Fig. 2 is a rear view of a garment embodying my invention, and Fig. 3 is a fragmentary perspective view showing the arrangement of the elastic member at the rear of the trousers portion of the garment.

The particular arrangement or kind of

fastening means may be varied without affecting my invention; or the buttons may be interchanged with buttonholes without affecting my invention.

Referring in detail to the drawings where-in similar reference characters denote similar parts throughout, 10 designates the waist or blouse portion of a child's garment and 11 designates the trousers portion thereof. 12, 13 and 14 designate the usual buttons or other fastening means at the front of the ordinary child's blouse or waist, 15, 16, 17 and 18 designate buttons which according to my invention are positioned at intervals on or near the waist band of the blouse and 60 are fastened to the blouse portion, 15 and 16 lying on the front right side of the waist and 17 and 18 lying on the front left side of the waist. 19 and 20 designate buttons which are fastened to the trousers portion of the 75 garment.

The trousers portion 11 is provided with buttonholes 21 and 22 which are so arranged at the waist band of the trousers portion that buttonhole 21 engages with button 15 of 80 the blouse portion and buttonhole 22 engages with button 18 of the waist portion.

The front of the trousers portion 11 is provided with a flap 23. At its upper edge flap 23 is provided with buttonholes 24, 25, 85 26, and 27 and at its sides with buttonholes 28 and 29.

When it is desired to fasten the trousers portion 11 on to the waist portion 10, buttonhole 28 and button 19 are brought into engagement as are buttonhole 29 and button 20.

Buttonhole 21 of the trousers portion is brought into engagement with button 15 of the waist portion and buttonhole 22 of the trousers portion is brought into engagement with button 18 of the waist portion. Buttonholes 24, 25, 26, and 27 of the flap 23 are brought into engagement with the buttons 15, 16, 17, and 18 of the blouse portion so that buttonhole 25 engages with button 15, 90 buttonhole 26 engages with button 16, buttonhole 27 engages with button 17 and buttonhole 24 engages with button 18.

30 and 31 designate the right and left trousers seams respectively, between which 105 points is located casing 32. Within casing 32 there is inclosed an elastic member 33 which has its ends fastened at points 30 and 31 respectively.

When the garment is in position on the 110

child tension by band 33 tends to hold the trousers portion against the body at the back. 34 designates a loose belt.

From the above description it will be seen 5 that my invention enables a child to get into its clothes and with facility completely arrange and fasten same without assistance, inasmuch as all the parts to be adjusted and all coöperative parts are arranged at the 10 front of the body and in view of the wearer.

Having thus described my invention, I claim as new and desire to secure by Letters Patent—

1. A child's garment comprising a trousers portion and a waist portion, said waist portion having at its front waist line fastening means for supporting the trousers portion which trousers portion is provided at its front with a flap whereon is arranged, 15 fastening means which coöperate with the fastening means of said waist portion and which trousers portion is provided at its back with an elastic member for holding the rear of the trousers portion in position 20 against the body.

2. A child's garment comprising a trousers portion having an elastic member positioned at the rear of the waist line and extending from side to side across the back 30 which elastic member is adapted to hold the rear of the trousers portion in position

against the body, and a panel opening out of the front portion of said trousers, said panel being provided with fastening means at its side edges whereby it may be separately 35 joined to the front portion to provide an uninterrupted waist line.

3. A child's garment, comprising the combination with a trousers member having fastening means at its front portion only, an 40 elastic member positioned at the rear of the waist line and extending from side to side across the back thereof, of a waist member having a skirt portion adapted to be introduced inside the upper portion of said trousers and against the body, said elastic member of said trousers adapted to normally engage the latter against said skirt portion to 45 yieldably hold the latter against the body, and means at the front portion of the waist 50 line of said waist to receive the fastening means of said trousers portion, whereby said trousers member and said waist member may be connected together at the front of the garment only so as to permit the waist to 55 be extensible within the trousers member at the back when the body is bent forward above the hips.

In testimony whereof, she has signed her name to this specification this 6th day of January, 1921.

LEAH JASLOW.
